UNITED STATES PATENT OFFICE.

JOHN TOWSTY, OF TORONTO, ONTARIO, CANADA, ASSIGNOR OF ONE-HALF TO WASYL CEPENDA, OF TORONTO, CANADA.

LOCK.

Application filed March 23, 1928. Serial No. 264,180.

This invention relates to certain new and useful improvements in locks and has for its primary object to provide a lock of the sliding bolt type in which permutation devices 5 associated with the sliding bolt are adapted to be operated to permit movement of the bolt under influence of an operating key.

A further object of the invention is to provide a lock of the sliding bolt type wherein 10 the bolt is key operated or shifted with control devices for the bolt, some of which are cooperative and operated by others to be moved to bolt releasing position whereby the bolt may be shifted by a key. 15 With the above and other objects in view that will become apparent as the nature of the invention is better understood, the same consists in the novel form, combination and arrangement of parts hereinafter more fully 20 described, shown in the accompanying drawings and claimed.

In the accompanying drawing, wherein like reference characters indicate corresponding parts throughout the several views,

25 Figure 1 is a fragmentary elevational view of a structure equipped with the improved lock construction, showing the operating head for the bolt control device,

30 Figure 2 is a horizontal sectional view showing the upper edge of the lock casing in elevation,

Figure 3 is a horizontal sectional view taken through the lock casing,

35 Figure 4 is a detail sectional view taken on line 4—4 of Figure 3 showing the pawl and ratchet mechanism associated with one of the control devices for the sliding bolt to prevent retrograde movement of the control device,

40 Figure 5 is a detail sectional view taken on line 5—5 of Figure 3 showing the sliding bolt projected from the lock casing,

45 Figure 6 is a cross-sectional view taken on line 6—6 of Figure 5 showing a spring 45 pressed pin constituting one of the control devices for the sliding bolt,

Figure 7 is a detail sectional view, similar to Figure 5 showing the bolt in retracted position,

50 Figure 8 is a cross-sectional view taken on line 8—8 of Figure 7,

55 Figure 9 is a cross-sectional view taken on line 9—9 of Figure 7,

Figure 10 is a detail sectional view of the

bolt control device shown in Figure 9 detached from the lock casing,

Figure 11 is a detail sectional view taken on line 11—11 of Figure 3,

Figure 12 is a perspective view of the lock bolt,

Figure 13 is a cross-sectional view taken on line 13—13 of Figure 12,

Figure 14 is a perspective view of a toothed wheel forming a part of one of the bolt controlled devices,

Figure 15 is a perspective view of the bolt controlled device with which the toothed wheel, shown in Figure 14, is associated,

Figure 16 is a detail sectional view taken on line 16—16 of Figure 15, showing the radial slit with which the key of the toothed wheel shown in Figure 14 is adapted to be associated for changing the combination of the bolt control device, and

Figure 17 shows in perspective the several elements of the bolt controlled device shown in Figure 10.

Referring more in detail to the accompanying drawings, it being understood that the lock is intended for different applications, 80 there is illustrated, a stationary member 1 and a movable member 2 with the lock structure carried by the movable member 2 and having its bolt engageable with the stationary member 1 to hold the member 2 against 85 movement, the lock construction comprising a casing having a bottom wall 1, side walls 2, end walls 3, and 4 and a removable top wall 5 retained in position by the screws 6 passing therethrough and entering lugs carried by the end walls of the lock casing. The lock casing is set into the recess formed in the movable member 2 and is retained therein by the fastening screws 7.

The lock casing incloses a sliding bolt 8 95 shown in detail in Figure 12, the bolt being of a length substantially the same as the lock casing so that the nose 8^a thereof is flush with the end wall 4 of the casing when retracted, the end wall 4 of the lock casing 100 having an opening 9 therein for the passage of the bolt and is further provided with a shoulder 10 bordering the opening to form a support for the nose end of the bolt. A longitudinally extending slot 11 is formed in the bolt and a longitudinally tensioned pin 12 that is supported at opposite ends in the top and bottom walls of the lock casing

passes through the bolt slot 11 and forms a support for the inner end of the bolt.

A plurality of devices engageable with the bolt 8 for controlling sliding movement there-
5 of are provided and these control devices in-
clude the pin 12, the pin 12 carries a later-
ally directed tapering lug 13 that is engage-
able in a similarly formed recess 14 formed
in a side wall of the bolt slot 11 to hold the
10 bolt against movement as will be evident from
an inspection of Figures 5 and 6. The pin
12 extends through the bottom wall 1 of the
lock casing and projects outwardly thereof
through the tubular boss 15 surrounding the
15 opening in the bottom wall 1 of the lock cas-
ing through which the pin extends. A but-
ton or cap 16 is fixed to the outer end of the
pin 12 while a coil spring 17 surrounds the
pin between the cap 16 and bottom wall 1
20 of the lock casing for normally holding
the lug 13 in the recess 14 of the bolt 8. The
lug 13 may be disengaged from the recess by
pressing inwardly upon the pin 12 by engag-
ing the cap 16 and a quarter turn imparted
25 to the pin will dispose the lug 13 in the slot
11 of the bolt as shown in Fig. 7 and permit
movement of the bolt when the other control
devices are moved to releasing positions rela-
tive to the bolt.

30 As shown more clearly in Fig. 12, the bolt
8 has one side thereof recessed at opposite
sides of the slot 11 as at 18 to provide a clear-
ance for part of other control devices for the
bolts. The end of the recess portion 18 adja-
35 cent the nose end 8^a of the bolt is cut
through to form a circular opening 18^a for
purposes presently to appear. A pair of con-
centric grooves 19 are formed in the outer
40 face of the bolt 8 and surround the circular
opening 18^a as illustrated. The detail parts
of another bolt control device are shown in
Figures 10 and 17 and comprise a stud crew
45 having a disk shoulder 21 that is journaled
in the bottom wall 1 of the lock casing as
shown in Figure 9 with an operating head 22
carried by the outer end of the stud crew 20.
The stud screw 20 carries a ratchet wheel 23
50 adjacent the bearing disk 21 while the stud
screw at the opposite side of the ratchet
wheel 23 carries an externally threaded
tubular bearing 24. The tubular bearing
24 of the stud screw is rotatable in the disk
55 plate 25, anchored as at 26 in the recess 27
formed in the bottom wall 1 of the lock cas-
ing and said disk plate carries a dog 28 that
is tensioned as at 29 for engagement with the
ratchet wheel 23 to prevent retrograde move-
60 ment thereof. A disk 30 is threaded onto the
tubular bearing 24 and carries spaced arcuate
edge flanges 31 projecting perpendicularly
from the disk plate 30 for association with
the arcuate grooves 19 in the bolt 8. When
65 the flanges 31 are engaged in the grooves 19,
the bolt 8 is retained against movement. The
flanges 31 are displaced from the arcuate

grooves 19 by operating the head or knob 22
that carries a stud screw upon which the
disk plate 30 is mounted and said flanges are
disposed in the position shown by dotted lines
in Figure 7 at opposite sides of the bolt 8. 70
As shown in Figure 1, the knob 22 carries an
arrow head or indicator 32 to register with
the character Figure 32^a on the lock casing for
determining the position of the flanges 31
with respect to the grooved portions 19 of the 75
bolt 8.

A toothed wheel 33 is fixed to the stub
shaft 34 that is journaled in the lock casing,
the stub shaft 34 projecting from one side
of the toothed wheel 33 while the other bear-
ing for the wheel comprises an oblong block
35 carrying an end pin 36 that is rotatably re-
ceived in the tubular bearing 24 of the stud
screw 20, the assembly being shown more
clearly in Figure 10. The stub shaft 34 car-
ries a collar 37 to space the toothed wheel 33
from the lock casing while the oblong block
35 at the opposite side of the toothed wheel
extends through the cut-out portion 18^a of
the recess 18 in the bolt 8. When the oblong 90
block 35 is positioned transversely of the bolt
slot 11, retraction of the bolt 8 into the cas-
ing is prevented as will at once be under-
stood from an inspection of Figure 11. De-
vices are provided for rotating the toothed 95
wheel 33 and oblong block 35 to position the
latter longitudinally of the bolt slot 11 as
shown in Figure 9 so that the bolt 8 can be
shifted. The operating means for the toothed
wheel 33 is shown more clearly in Figures 8 100
and 14 to 16 and comprises a bearing stud 38
journaled in the bottom wall 1 of the lock cas-
ing and extending through the slot 11 in the
bolt 8 with an enlarged head 39 upon its inner
105 end that is positioned in the recessed portion
18 of the bolt. The outer end of the bearing
stud 38 is reduced and threaded for the re-
ception of the operating knob 40 that carries
an integral rotatable dial plate 41 readable
110 in connection with a character 41^a upon the
lock casing. The head 39 is provided with
a plurality of radial grooves 42 opening at
their inner sides in an axial bore 43 into
which bore the bearing shaft 44 carrying
the toothed wheel 45 is removably received, 115
the other end of the bearing shaft being jour-
naled in the top wall 5 of the lock casing. The
shaft 44 carries a key 46 positionable in a de-
sired one of the radial slots 42 to vary the
position of the key 46 relative to the gradu-
ations upon the dial 41. The disk wheel 45
120 is placed in meshing engagement with the
toothed wheel 43 and when the knob 40 is
rotated to rotate the wheel 45, rotation is im-
parted to the wheel 33 for shifting the oblong
block 35 relative to the slot 11 in the bolt 8
for controlling movement of the latter.
From the above detailed description of the
invention, it is believed that the construction
and operation thereof will at once be appar- 125
130

ent, it being noted that the operation of the bolt 8 is controlled by manually operable permutation devices and when said devices are shifted to positions to permit sliding movement of the bolt, a key is inserted through the key opening 47 in the lock casing with the ward thereof positioned for engagement with the lugs 48 carried by the upper side of the bolt as indicated in Figure 7. The knob 22 operates the disk 30 to displace the arcuate flanges 31 from the arcuate grooves 19 in the bolt 8, while the knob 40 operates the toothed wheel 45 which in turn rotates the toothed wheel 33 to position the oblong block 35 longitudinally of the bolt slot 11 so that the bolts may be shifted. The lug 13 upon the pin 12 is then displaced from the side notch 14 in the bolt slot by operating the knob 16 and the bolt is then free 20 to be moved.

While there is herein shown and described the preferred embodiment of the present invention, it is nevertheless to be understood that minor changes may be made therein without departing from the spirit and scope of the invention as claimed.

What I claim as new is:—

1. In a lock of the character described, a lock casing, a sliding bolt therein, a plurality of devices associated with the bolt for controlling sliding movement of the same, one of said devices comprising a rotatable disk, spaced arcuate flanges extending from one face of the disk and said bolt having 30 grooves therein to receive the flanges, and being longitudinally slotted, a stub shaft journalled in the casing and having a rectangular block within the slot, said slot having a lateral enlargement to permit transverse positioning of the block to hold the bolt against movement, and one of the bolt control devices being operable to position the block in the bolt slot to permit sliding movement of the bolt.

2. In a lock of the character described, a lock casing, a sliding bolt therein, a plurality of devices associated with the bolt for controlling sliding movement of the same, one of said devices comprising a rotatable disk, spaced arcuate flanges extending from one face of the disk and said bolt having grooves therein to receive the flanges, and being longitudinally slotted, a stub shaft journalled in the casing and having a rectangular block within the slot, said slot having a lateral enlargement to permit transverse positioning of the block to hold the bolt against movement, a toothed wheel fixed to the stub shaft, another shaft journalled in the casing, a toothed wheel thereon engaged with the aforesaid toothed wheel, and means for operating the second shaft.

3. In a lock of the character described, a lock casing, a sliding bolt therein, a plurality of devices associated with the bolt for con-

trolling sliding movement of the same, one of said devices comprising a rotatable disk, spaced arcuate flanges extending from one face of the disk and said bolt having grooves therein to receive the flanges, and being longitudinally slotted, a stub shaft journalled in the casing and having a rectangular block within the slot, said slot having a lateral enlargement to permit transverse positioning of the block to hold the bolt against movement, 70 a toothed wheel fixed to the stub shaft, another shaft journalled in the casing, a toothed wheel thereon engaged with the foresaid toothed wheel, means for operating the second shaft, and an adjustable engagement between the second shaft and toothed wheel, whereby movement of the second toothed wheel is varied in positioning the block in bolt releasing position.

4. In a lock of the character described, a lock casing, a sliding bolt therein, a plurality of devices associated with the bolt for controlling sliding movement of the same, one of said devices comprising a rotatable disk, spaced arcuate flanges extending from one 90 face of the disk and said bolt having grooves therein to receive the flanges, and being longitudinally slotted, a stub shaft journalled in the casing and having a rectangular block within the slot, said slot having a lateral enlargement to permit transverse positioning of the block to hold the bolt against movement, a toothed wheel fixed to the stub shaft, another shaft journalled in the casing, a toothed wheel thereon engaged with the aforesaid toothed wheel, means for operating the second shaft, an adjustable engagement between the second shaft and toothed wheel comprising a radially slotted head on the shaft, and a key on the wheel selectively 100 positioned in a slot whereby movement of the second toothed wheel is varied in positioning the block in bolt releasing position.

5. In a lock of the character described, a lock casing, a sliding bolt therein having a longitudinal slot and concentric arcuate grooves in one side face thereof, a tumbler disk journalled on a pin extending through the bolt slot and disposed at the grooved side of the bolt and arcuate flanges on the disk 110 adapted to enter the grooves for holding the bolt in projected locked condition.

6. In a lock of the character described, a lock casing, a sliding bolt therein having a longitudinal slot and concentric arcuate 120 grooves in one side face thereof, a tumbler disk journalled on a pin extending through the bolt slot and disposed at the grooved side of the bolt and arcuate flanges on the disk adapted to enter the grooves for holding the bolt in projected locked condition, and said bolt and pin being cooperatively constructed to further hold the bolt locked.

7. In a lock of the character described, a lock casing, a sliding bolt therein having a 130

longitudinal slot and concentric arcuate grooves in one side face thereof, a tumbler disk journaled on a pin extending through the bolt slot and disposed at the grooved side of the bolt, arcuate flanges on the disk adapted to enter the grooves for holding the bolt in projected locked condition, the walls

of the bolt slot having opposite notches therein and a block operated by the pin extending through the slot, adapted to be transversely positioned in the side notches to hold the bolt locked. 10

In testimony whereof I affix my signature.
JOHN TOWSTY.
